SPOTTING TOOL

Original Filed July 11, 1927

INVENTOR.
LOUIS A. FAURE.
By *Cuthbert S. Lee*
ATTY.

UNITED STATES PATENT OFFICE.

LOUIS A. FAURE, OF SAN FRANCISCO, CALIFORNIA.

SPOTTING TOOL.

Application filed July 11, 1927, Serial No. 204,902. Renewed April 1, 1929.

My invention relates to improvements in tools for removing dents from sheet metal and particularly for removing small dents from the fenders of automobiles.

5 The primary object of my invention is to provide an improved dent removing tool.

Another object is to provide an improved tool which will facilitate the spotting and removing of small dents.

10 A further object is to provide a tool of the character described wherein any of a variety of hammers may be detachably mounted for beating out dents of various kinds and sizes.

15 Another object is to provide an improved tool provided with improved means for detachably securing a hammer thereon to facilitate the interchange of hammers and to insure alinement with a beating block.

20 A still further object is to provide an improved tool of simple and rugged construction and increased efficiency.

I accomplish these and other objects by means of the improved device disclosed in 25 the drawings forming a part of the present application wherein like characters of reference are used to designate similar parts throughout the specification and drawings and in which,

30 Fig. 1 is a side elevation of my improved dent removing tool, parts being broken away and shown in section.

Fig. 2 is a broken plan view of the tool.

35 Fig. 3 is a front elevation of the tool as shown in Fig. 1.

Fig. 4 is a sectional detail drawn upon a larger scale and showing the manner in which the block and hammer engage opposite sides of a dented member.

40 Fig. 5 is a side elevation of one form of hammer.

Fig. 6 is a side elevation of a different form of hammer.

45 Fig. 7 is a left side elevation of the hammer as shown in Fig. 6.

Referring to the drawings, the numerals 1 and 2 are used to designate a pair of arms having curved ends hingedly connected as at 3. An inwardly offset beating block 4 is

50 formed upon the free end of the arm 1, said block having a flat lower face arranged to engage the surface of a dented member 6 such as an automobile fender. An opening 7 is formed through the block 4 through

which the surface of the member 6 may be 55 observed for spotting the block directly over a dent 8 to be removed as best shown in Fig. 4 of the drawings.

A hammer 9 is detachably mounted upon the free end of the opposite arm 2, said hammer being of any suitable size and form for beating out small dents. The hammer 9 is mounted upon the arm 2 by means of a mounting portion 11 having an angularly disposed extension 12 enlarged upon the outer end. 60 The extension 12 is arranged to be slidably engaged by a T slot 13 formed in the arm 2, and is provided with a pin 14 arranged to engage an opening formed in a plunger 16 65 slidably mounted within the end of the arm 2. A spring 17 mounted within the end of the arm 2 normally holds the plunger against a stop 18 formed adjacent the enlarged portion of the T slot 13. A hook portion 19 is formed opposite the mounting arm 11 and 70 arranged to hook over the end of the arm 2. In mounting a hammer 9, the extension 12 is inserted into the wide portion of the T slot 75 13 and the pin 14 is introduced into the opening in the plunger 16. The hammer is then 80 moved toward the end of the arm 2 and the hook portion caused to engage the end of said arm 2 as shown in Fig. 1 of the drawings, the plunger 16 being moved to compress the 85 spring 17. The spring 17 holds the hook in locking engagement with the end of the arm 2. The hammer 9 is arranged in alinement with the opening 7 in the block 4 when the hammer is in locked position upon the arm 2.

In Figs. 6 and 7 I have illustrated a form 90 of hammer wherein a plurality of hammer heads 9 are formed upon a hub 21 rotatably mounted upon a pin 22 slidably mounted upon a post 23 arranged to be mounted upon the arm in the manner above described. A 95 cam 24 is pivotally mounted upon the end of the pin 22 and arranged to bear against the outer face of the post 23. A spring 26 is mounted within a recess formed in the hub and arranged to bear against the inner face 100 of the post 23 and arranged to exert a pressure tending to move pin 22 through the post 23 and the hub 21 away from said post. A pin 27 mounted upon the post is arranged to engage any of a plurality of openings 28 105 formed in the hub to prevent rotation of the hub when said hub is moved against the post. The cam is arranged to move the pin 22 and

hub 21 transversely to the post 23 to disengage the pins 27 whereby the hub may be turned to present the desired hammer head 9 for engagement with the dented member.

5 In operation, the arms 1 and 2 are spread apart sufficiently to move upon opposite sides of the dented member 6. The block 4 is placed upon the surface of the member 6 directly over the dent to be removed, the opening 7 being positioned directly over the point where it is desired to have the hammer 9 strike. The arm 2 is then swung upon its hinge connection to cause the hammer 9 to strike the surface of the member 6 opposite to the block 4, thereby beating out the dent. The opening 7 permits the block to be spotted to exactly the desired position and indicates the exact point at which the hammer 9 will strike when the arm 2 is swung upon its pivot, 20 in this manner permitting the dent to be quickly and easily beaten out without waste of time or energy in locating the exact point upon which to deliver blows for beating out the dent.

25 A plurality of hammers 9 of different size and form are provided in order that a hammer which will best serve to beat out any particular dent may be selected and applied upon the arm 2. The hammers are quickly and 30 easily removed by moving the hammer forwardly enough to cause the hook 19 to disengage the end of the arm 2, and then moved rearwardly out of engagement with the T slot, thus permitting a different hammer to be 35 substituted.

In the modified form of hammer shown in Figs. 6 and 7, the cam 24 is moved to release the hub 21 whereby the hub may be turned to present a desired hammer head to the work. The gang hammer shown may be interchanged with single hammers of various forms as desired.

The device is particularly useful for removing small dents from automobile fenders and bodies, the arms 1 and 2 being made of sufficient length and weight to reach portions of such fenders or bodies remote from the edges thereof, and to deliver an effective blow at exactly a desired point. The device 50 may of course be made in various sizes and weights to adapt it for use in other connections.

While I have illustrated and described only the preferred embodiment of my invention, 55 the device is of course subject to modification in numerous ways without departing from the spirit of the invention. I, therefore, do not wish to restrict myself to the specific details of construction illustrated and described, 60 but desire to avail myself of all modifications which may fall within the scope of the appended claims.

Having thus described my invention what I claim as new and desire to secure by Letters Patent is:

1. A tool for removing dents from sheet metal comprising a pair of arms hingedly connected at one end and arranged to extend upon opposite sides of a dented member; a block formed upon the free end of one arm 70 to rest against one side of the dented member, said block having an opening therethrough for spotting the block over a dent; a hammer detachably mounted upon the free end of the other arm to strike the dented member opposite the block; and means for normally locking the hammer in alinement with the opening in the block.

2. A tool for removing dents from sheet metal comprising a pair of arms hingedly 80 connected at one end and arranged to extend upon opposite sides of a dented member; a block formed upon the free end of one arm to rest against one side of the dented member; a hammer; an extension formed upon the base of the hammer to slidably engage a T slot formed in the other arm; a hook formed upon the hammer to engage the end of said other arm; and a spring mounted within the arm and engaging the extension to normally hold the hook in locking engagement with the arm.

3. A tool for removing dents from sheet metal comprising a pair of arms hingedly 95 connected at one end and arranged to extend upon opposite sides of a dented member; a block formed upon the free end of one arm to rest against one surface of the dented member, said block having an opening therethrough for spotting the block over a dent; a hammer mounted upon the other arm in alinement with the opening in the block, said hammer being carried by a mounting member 100 slidably engaging said other arm; locking means carried by the mounting member; and a spring engaging the mounting member and arranged to hold the locking means in detachable locking engagement with the arm.

4. A tool for removing dents from sheet metal comprising a pair of arms hingedly 110 connected at one end and arranged to extend upon opposite sides of a dented member; a block formed upon the free end of one arm to rest against one surface of a dented member; a hammer mounting member slidably 115 and detachably engaging a slot formed in the free end of the other arm; a hook formed upon said mounting member and arranged to engage the arm to detachably lock the member in engagement therewith; a spring normally holding the member in locked position; and a hammer carried by the mounting member in alinement with the block.

5. A tool for removing dents from sheet metal comprising a pair of pivotally connected arms arranged to extend upon opposite sides of a dented member; a block formed upon the end of one arm to rest against one surface of a dented member, said block having an opening formed therethrough for 125 130

spotting the block over a dent; a hammer mounting member slidably and detachably engaging a slot formed in the free end of the other arm; a locking hook formed upon said mounting member and arranged to engage the arm to detachably lock the member in engagement therewith; a spring normally holding the member in locked position; and a hammer carried by the mounting member in alinement with the opening in the block.

In witness whereof, I hereunto set my signature this 2nd day of July, 1927.

LOUIS A. FAURE.
